UNITED STATES PATENT OFFICE.

ARTHUR E. PETERS, OF PHILLIPSBURG, NEW JERSEY, AND JESSE DITSON, OF LITTLETON, COLORADO, ASSIGNEES TO INGERSOLL-RAND COMPANY, OF JERSEY CITY, NEW JERSEY, A CORPORATION OF NEW JERSEY.

SHANK AND BIT PUNCH.

Application filed September 9, 1927. Serial No. 218,465.

This invention relates to devices for reforming the bores of hollow articles, but more particularly to a fluid actuated device for pinning out the ends of the bores in drill 5 steels and other similar articles in which the entrance of the bores frequently become restricted during the preceding sharpening operation.

One object of the invention is to drive a 10 punch pin into the bore of a drill steel and withdraw it therefrom by rapidly repeated blows of the hammer piston against the anvil block whereby the punch pin is carried.

Another object is to provide a convenient 15 means for controlling the admission of pressure fluid into the percussive element of the punch.

Other objects will be in part obvious and in part pointed out hereinafter.

20 In the drawings showing a preferred modification of the invention,

Figure 1 is a longitudinal sectional elevation of a shank and bit punch constructed in accordance with the practice of the invention and showing the parts in position for driving the punch pin into the work,

25 Figure 2 is a view similar to Figure 1 illustrating the position of the parts for withdrawing the punch pin from the work,

30 Figure 3 is a transverse view of the centering chuck taken through Figure 1 on the line 3—3 looking in the direction indicated by the arrows, and

35 Figure 4 is a similar view of the throttle valve lever taken through Figure 1 on the line 4—4 looking in the direction indicated by the arrows.

Referring to the drawings, A designates 40 the cylinder of a shank and bit punch and B the piston chamber in which is disposed a reciprocating hammer piston C. The piston chamber B comprises an enlarged forward portion D and a rearwardly reduced portion E. The piston C is proportioned accordingly and its rearward reduced portion 45 F in this instance is constantly exposed to pressure fluid during the operation of the machine.

Disposed at the front end of the cylinder 50 A and projecting partly thereinto is a front head G which may be secured in operative position in any suitable manner as for instance by the usual side bolts (not shown). The rearward end of the cylinder A is sealed

by a back cylinder washer H which forms a 55 seat for and serves to centralize a cylinder cap J with respect to the cylinder.

On one side of the cylinder A is formed a tapered valve chamber K to accommodate a correspondingly tapered throttle valve L having a passage O in constant communication with pressure fluid conveyed to the throttle valve from any suitable source of supply by a connection P. The throttle valve L in this instance is provided with a stem Q which is 65 supported at its outer end by a bearing R preferably formed integrally with the cylinder A and so spaced with respect to that portion of the cylinder wherein the valve chamber K is formed as to form a space S of 70 suitable proportions to receive a throttle valve lever T whereby the throttle valve L may be manipulated.

The throttle valve lever T comprises oppositely extending portions U and V curved 75 slightly at their ends to prevent deflection of such instrument or means as may be employed for manipulating the throttle valve. Intermediate the ends of the throttle valve lever is formed a bore W to receive slidably 80 the stem Q and in one side of the lever adjacent the bore W is formed a slot X to permit contraction of the lever at this point for the purpose of clamping said lever to the stem Q. The means whereby this clamping effect is obtained in the present instance consist of a bolt Y which engages a notch Z in the stem Q and has threaded on one end a nut b whereby the desired clamping effect may be obtained.

90 In its assembled position, the throttle lever T will be inclined both in the open and closed positions of the throttle valve L, the degree of rotation of said throttle valve being limited by the cylinder in the bottom 95 of the space S which forms an abutment for the throttle lever on opposite sides of the stem Q.

100 In one side of the throttle valve L is a port c to afford communication between the passage O and a port d in the cylinder A for the passage of pressure fluid into the piston chamber B. The port d is in constant communication with a passage e having rearward and forward ports f and g both of 105 which open into the reduced bore E of the cylinder.

As is customary in devices employing pis-

tons of the type disclosed, the admission of pressure fluid from the port *g* into the piston chamber is intermittent and is controlled by the stem *h* of the piston *C*. At the juncture of the head of the piston *C* and the stem *h* is formed a reduced neck *j* around which the pressure fluid from the port *g* passes into the rearward end of the enlarged portion *D* of the piston chamber *B* for impelling the piston forwardly.

Pressure fluid is conveyed to the front end of the piston chamber *B* for impelling the piston *C* rearwardly through an inlet passage *k* which opens into the piston chamber *B* near its front end and has its entrance end *o* intermediate the ports *f* and *g*.

Intermediate the ends of the enlarged portion *D* of the piston chamber *B* is formed an exhaust port *p* for exhausting the pressure fluid from both ends of the enlarged portion *D*, said exhaust port being controlled by the head of the piston *C*.

Extending slidably through the front head, the cylinder and the piston is an anvil block *q* having a recess *r* in its front end to receive a punch pin *s* adapted to be driven into a hollow drill steel *t*. The punch pin *s* may be secured in the anvil block *q* in any suitable manner, in the present instance a pin *u* extending transversely through the anvil block and the punch pin is used for this purpose.

The anvil block *q* illustrated is of a length to extend through the cylinder *A* and, in its retracted position through the cylinder cap *J*. The anvil block is guided in this instance near its front end by the front head *G* and at a point near its rearward end by the back cylinder washer *H*.

Near the front end of the anvil block *q* is a collar *v* which, when the anvil block *q* is in its rearwardmost position, extends into the path of the piston *C* to receive the blows thereof for driving the punch pin *s* into the drill steel *t*. Somewhat similar means are provided for exposing the anvil block *q* to the blows of the piston *C* for driving said anvil block in a rearwardly direction. These means in the present instance consist of a pair of semi-cylindrical collars *w* which lie in a groove *y* in the anvil block *q* and are held against lateral movement by a coil spring *z* which snugly engages the periphery of said collars *w* to hold them in the groove *y*.

Means are provided for restoring the anvil block *q* to an intermediate position whenever the pressure used for actuating the anvil block is released therefrom. The means employed for this purpose consist of a pair of rearward collars *2* which may abut a shoulder *3* in the cylinder cap *J* and are disposed slidably on the rearward end of the anvil block *q*. An opposed pair of collars *4* are similarly disposed about the anvil

block forwardly of the collars *2* to seat either against a shoulder *5* of the anvil block or against the rearward surface *6* of the back cylinder washer *H*, depending upon the position of the anvil block *q*. The collars *2* and *4* are held in assembled position by a compression spring *7* which encircles them and also acts thereagainst for actuating the anvil block *q* whenever the pressure exerted on said anvil block for compressing the spring *7* is released. At the rearward end of the anvil block *q* is formed a shoulder *8* which, when the anvil block is drawn forwardly, may engage the collars *2* for compressing the spring *7*.

A convenient support for the drill steel *t* is provided in the form of a centering chuck *9* having a fork *10* so located with respect to the punch pin *s* that when the drill steel *t* is disposed within said fork *10*, the hollow portion of the drill steel will lie in substantially the same plane as the longitudinal axis of the punch pin *s*. The centering chuck in this instance is mounted on a rod *11* whereto it is clamped by means of a bolt *12*. The rod *11* extends into an aperture *13* in the cylinder *A* and is held both against rotative and longitudinal movement by a pin *14* extending transversely through the cylinder and the rod.

The operation of the device briefly described is as follows: Let it be assumed that at the beginning of the operation, the anvil block *q* is in the intermediate position hereinbefore referred to, that is, the position to which it will be automatically actuated by the spring *7*. If then, it be desired to drive the punch pin *s* into the drill steel *t*, the attendant may strike a blow on the end *V* of the throttle lever *T* to oscillate said throttle lever to the position indicated in Figure 4. In this position, the throttle valve will be open and pressure fluid may then flow through the ports *c* and *d* into the passage *c*, thence into the rearward end of the reduced portion *E* of the piston chamber *B* as well as into the rearward end of the enlarged portion *D* of the piston chamber for actuating the piston forwardly against the collar *v* of the anvil block, it being of course understood that the pressure of the drill steel *t* against the punch pin *s* will be sufficient to compress the spring *7* as shown in Figure 1 and thus move the collar *v* into the path of the hammer piston *C*. At about the time the piston *C* is delivering its blow against the collar *v* the rearward end of the passage *k* will be uncovered by the piston, thus permitting the flow of pressure fluid through the passage *k* into the front end of the piston chamber *B* to drive the piston *C* rearwardly. This reciprocation of the piston *C* may continue until the restricted portion of the bore in the drill steel *t* has been satisfactorily opened.

As is well known, the chilling effect of the punch pin *s* on the heated end of the drill steel *t* will cause the said drill steel to contract on the punch pin *s* to such an extent that it will cling thereto with sufficient force to enable the anvil block to be pulled to its extreme forward position whenever a pull on the drill steel is exerted. As a result the anvil block *q* may be moved forwardly to such a position that the collar *v* will be withdrawn out of the range of the blows of the hammer piston *C* and the collars *w* will then be advanced sufficiently to expose them to the blows of the rearward end of the piston *C*. In this way the punch pin *s* will be readily withdrawn from the drill steel thus permitting the spring *7* to expand and force the anvil block *q* to its intermediate position. In this position of the anvil block, the collars *2* will bear against the collar *B* of the anvil block and the collars *4* against the surface *6* of the back cylinder washer *H* and the anvil block *q*.

After the punching operation has been completed, the attendant may, by dropping the drill steel *t* on the end *U* of the lever *T*, tip the lever to its other extreme position, thus closing the throttle valve *L* and shutting off the supply of pressure fluid to the cylinder.

As will be readily seen, the present device forms a complete and compact unit of light weight and simple construction for punching hollow articles. The method of controlling the admission of pressure fluid to the punch is extremely simple as compared with other well known devices of this type. In its extreme positions, the throttle lever *T* is inclined, thus indicating at all times the

exact position of the throttle valve *L*. This is a desirable feature in devices of this character since it tends to eliminate accidents such as sometimes happen when the supply of air to the device is temporarily cut off and shortly afterwards again turned on without closing the throttle valve.

We claim:

1. In a shank and bit punch the combination of a cylinder and piston, an anvil block extending through the piston, a punch pin carried by the anvil block and shoulders on the anvil block adapted to be selectively exposed to the blows of the piston for driving the punch pin into and out of the article intended to be punched, one of said shoulders comprising a pair of collar members encircling said anvil block and a spring holding said members in position on said block.

2. In a shank and bit punch the combination of a cylinder, a piston having a hollow end, an anvil block extending through the piston, a punch pin carried by the anvil block, shoulders on the anvil block adapted to be selectively exposed to the blows of the piston for driving the punch pin into and out of an article intended to be punched, one of said shoulders comprising a pair of collar members encircling said anvil block, a spring holding said members in position on said block and a neck on said anvil block adapted to receive the collar members, said piston being adapted to slide over said collar members at its hollowed end.

In testimony whereof we have signed this specification.

ARTHUR E. PETERS.
